United States Patent Office.

RICHARD H. CUTTER, OF CLEVELAND, OHIO.

Letters Patent No. 61,610, dated January 29, 1867.

IMPROVED BED-LOUNGE.

The Schedule referred to in these Letters Patent and making part of the same.

TO ALL WHOM IT MAY CONCERN:

Be it known that I, RICHARD H. CUTTER, of Cleveland, county of Cuyahoga, in the State of Ohio, have invented a new and improved Bed-Lounge; and I do hereby declare that the following is a full and exact description thereof, reference being had to the accompanying drawings, and to the letters of reference marked thereon.

Figure 1 is a perspective view of the lounge.

Figure 2 is a view of the same when unfolded and converted into a bed.

Figure 3 is an end view representing the receptacle in the head for the deposit of the loose bed-clothing when not in use.

Figure 4 is a vertical cross-section.

The nature of this invention consists in constructing a settee or lounge in such a manner that it may be readily converted into a commodious bed, and at the same time supplying within itself a suitable receptacle for the storing of loose bed-clothing when not required for use.

To enable others to understand my improvement, I will describe its construction and operation.

A represents the seat of a lounge, which may be upholstered in any of the known styles, but I have made the lounge seat double, so as to be unfolded. The upper or folding seat A is hinged in front to the main lounge, and may be turned over, and thereby converted into a comfortable bed, as seen in fig. 2. The bed is constructed in the form of a mattress, M, of curled hair or other suitable material, and forms a part of the whole structure. The two rails in the centre B are cut away in part, except at the ends, so as not to obstruct the formation of a continuous or complete mattress, which would otherwise render the bed uncomfortable. The head C of my improved lounge I make hollow, and in two separate parts or halves, seen in fig. 3. The folding half g is hung by a hinge, e, in order that it may be opened, and form the complete head-board to the bed when desired for that use. There is a hook, i, used to fasten the folding head to the folding seat A. It also serves to fasten the head when closed at j. t t represent legs or supports for the folding seat A when open. They may be turned up and hid in pockets in the side when not in use. Across the lower end of the bed there is an elastic strap, v, to hold the bed-covering in place.

I am aware that the construction of a folding seat of a lounge or sofa to form a bed is not new, but I have obviated one of the difficulties by removing a portion of the front or centre railing, and forming a continuous mattress. I have constructed the head of the lounge in the manner described for a receptacle for bed-clothing, thus rendering the improved lounge more serviceable, equally useful as a lounge or sofa during the day, and a comfortable, convenient bed at night.

What I claim as my improvement, and desire to secure by Letters Patent, is—

The combination, with the folding seat A, the mattress M and the folding head C, when constructed and operating in the manner and for the purpose herein specified.
